Attorneys.

UNITED STATES PATENT OFFICE.

GABRIEL BLUM, OF PHILADELPHIA, PENNSYLVANIA.

GARMENT.

1,323,572.

Specification of Letters Patent.

Patented Dec. 2, 1919.

Application filed May 24, 1919. Serial No. 299,570.

To all whom it may concern:

Be it known that I, GABRIEL BLUM, a citizen of the United States, and a resident of the city of Philadelphia, county of Philadelphia, and State of Pennsylvania, have invented certain new and useful Improvements in Garments, of which the following is a specification, reference being had to the accompanying drawing.

10 My invention relates to pockets in garments and is especially adapted for employment in men's or boys' trousers, although it may be utilized in other garments such as ladies' skirts or the like.

15 The principal object of my invention is to provide in a garment a safety pocket for carrying valuables or the like, which, when closed, will be inconspicuous and in fact very largely concealed, and to which access 20 may be gained only by unfastening or completely removing the fastening means employed to hold the closure of the pocket in closed position. A further object of my invention is to provide a safety pocket arranged in conjunction with a pocket of ordinary form in such manner that a thief or pickpocket will naturally insert his hand in the ordinary pocket which will generally be employed for carrying articles of small 25 value without being aware of the presence of the safety pocket adjacent thereto and in which the more valuable articles of the wearer are deposited. Still further objects of my invention are to provide in a garment 30 a safety pocket of inconspicuous appearance to which access may be readily gained by the wearer but which, when closed will securely retain articles deposited therein and protect them from unauthorized abstraction; to pro- 35 vide a safety pocket disposed adjacent to and in coöperative relation with an ordinary pocket in the garment, which in no way interferes with access thereto and which by its novel arrangement, construction and coöperation with the ordinary pocket will lead a thief or pickpocket to the belief that the 40 valuables of the wearer are deposited in such ordinary pocket so that his attention will be devoted to abstracting the contents thereof 45 without searching for and endeavoring to abstract the contents of the safety pocket.

45 My invention further includes all of the other various objects and novel features of construction and arrangement hereinafter 50 more definitely specified and described.

In the accompanying drawings I have illustrated my invention in connection with a pair of men's trousers, although it will be understood that I do not thereby desire or intend to confine myself to the use of the invention solely in a garment of this nature, Figure 1 being a perspective view of a pair of trousers embodying the invention and showing the parts in position to give access to the safety pocket, while Fig. 2 is a fragmentary view showing the parts in substantially the position assumed when the safety pocket is closed, certain of them, however, being shown in slightly distorted position for the sake of clearness as will be fully explained hereinafter.

The trousers illustrated in the drawing have the usual waist band 1, legs 2, belt loops 3, hip pocket 4 and waist strap 5 which, however, form no part of the invention. The trousers are provided with the usual side seam 6 adjacent the upper extremity of which is formed a side pocket 7 in the usual manner, the body 8 of the pocket being shown in dotted lines, and access being gained thereto through the substantially vertically or longitudinally disposed mouth or opening 9 adjacent the side seam of the trousers, extending from near the waist band downwardly for a sufficient distance to readily admit the hand of the wearer.

Adjacent and preferably substantially superimposed on the pocket 7 is another or safety pocket 10 having a body 11 preferably slightly smaller than the body 8 as shown in the drawing, arranged to lie between the pocket 7 and the material of the leg 2 of the garment, which material is arranged to form a substantially triangular closure or flap 12 for this pocket. One extremity or corner 14 of the flap is disposed adjacent the waist band of the trousers and the other extremity or corner 15 adjacent the edge of the material which forms one side of the opening 9, suitable stitching 17 and 18 preferably extending completely through said material being provided at these points. That edge of the flap extending upwardly from corner 15 may preferably be arranged to substantially coincide with the edge of the opening 9, when the flap is closed, while the other edge extends substantially at right angles thereto adjacent the waist band 1, so that, with the flap turned to the position shown in Fig. 1 an opening disposed in

angular relation to opening 9 is formed through which access is gained to the body of the pocket.

The material of which the garment is made is preferably extended downwardly from the waist band to join the body 11 of the pocket 10, which will ordinarily be formed of a different kind of material, approximately at the line 20 so that when the flap is turned down as shown in Fig. 1 the material forming the body of the pocket will not be visible. For the purpose of securing the flap or closure 12 and thus closing the pocket when desired, the flap is preferably provided with a plurality of button-holes 22 adjacent its upper edge co-operative with corresponding buttons 23 positioned adjacent the waist band of the garment. It will be understood that, if preferred, any other convenient means for retaining the flap in closed position may be employed for example, snap or glove fasteners or the like, and that while but two buttons are shown in the drawing, any desired number thereof, or of the other fastening means, may be utilized.

In Fig. 2 the flap or closure 12 of the pocket is illustrated in closed position, that is, in the position in which it will normally be worn, and for the sake of clearness the opening 9, through which entrance is gained to the pocket 7, is shown as pulled or gaped open rather more than it would ordinarily be when the garment is worn; that is, the parts are shown in approximately the position which they would assume when the hand is being introduced into the pocket 7, during which operation the flap moves unitarily with the material forming the side 40 of opening 9. It will be noted that the stitching 18 at the lower extremity of flap 12 is positioned less than half way from the upper end of the opening 9 to the lower end thereof, so that with the flap 12 in closed position it is impossible to introduce the hand into the safety pocket adjacent the edge of the opening 9, or adjacent the upper edge of the flap on account of the buttons 23 or other fastening means, and, further, that the flap 50 lies very closely to the edge of the opening 9 so that the fingers will naturally slip into said opening leading to the pocket 7 and not into the very small, substantially closed and practically concealed opening leading to the pocket 10. Access, however, may, when desired, be readily gained to the pocket 10 by unbuttoning the flap as shown in Fig. 1, after which the hand may be easily introduced into the pocket.

60 It will be observed that by reason of the fact that the body 11 of the safety pocket is interposed between the body of the ordinary pocket 7 and the material of which the garment is made, it is impossible to tell from

observation of the exterior of the garment 65 that the contents of the safety pocket are disposed in a receptacle separate from but adjacent to the body of the ordinary pocket so that, for example, if a roll of bills be carried in the safety pocket and a bunch of 70 keys or other relatively non-valuable articles in the ordinary pocket the bulge produced thereby on the exterior of the garment would lead a thief to the conclusion that all of the articles which tended to produce it were disposed in the pocket 7 and an attempt to abstract these articles would therefore be directed to this pocket alone. Such attempt, however, if successful, would result only in the abstraction of the relatively non-valuable articles contained in the ordinary pocket. It will be further noted that in ordinary use, that is, when articles are placed in or removed from the ordinary pocket 7, the material forming the safety 80 pocket moves unitarily with and in no way interferes with the employment or operation of the former, and that, on the other hand, articles may be readily removed from or introduced into the safety pocket after the 90 flap is unfastened without disturbing the contents of the ordinary pocket, the two pockets being in effect separate but so combined in the garment as to form a single unitarily operative device so constructed as 95 to present, especially when the garment is worn with a vest, the lower part of which is operative to cover the buttons or other fastening means of the flap, the appearance of an ordinary pocket while providing a 100 readily accessible and yet securely closed receptacle for articles of value.

It will be understood that while I have illustrated the invention as applied only to one side of a pair of trousers, in practice it 105 is customary to apply it to both sides thereof, and furthermore, that it is equally adapted for employment in forms of garments other than men's trousers. I therefore do not desire or intend to limit myself solely to 110 its use therein or to the specific details of construction and arrangement of the various parts as herein illustrated and described, as suitable changes and modifications may be made in such details without departing 115 from the spirit and scope of the invention as defined in the appended claims.

Having thus described my invention, what I desire to claim and protect by U. S. Letters Patent is—

1. In a garment, the combination of a pair of pockets having independent relatively angularly disposed openings, one of said pockets being disposed between the other of said pockets and material of said 125 garment, and having a closure comprising a flap and means for securing said flap in closed position.

2. In a garment, the combination of a plurality of pockets having independent openings, said openings being disposed in relative angular relation, a closure for one 5 of said openings comprising a flap extending from adjacent the edge of the other of said openings, and fastening means for said closure.
3. In a garment, the combination with a 10 pocket having an opening adjacent a side seam of the garment and extending substantially in alinement therewith, of another pocket disposed between said first mentioned pocket and the material whereof the garment is made and having an opening angularly disposed with respect to said first mentioned opening, a flap for said last mentioned pocket formed of said material, one edge of said flap when in closed position 15 lying adjacent the edge of the opening to said first mentioned pocket and means adjacent the other edge of said flap to maintain said flap in closed position.
4. In a garment, the combination of a 20 plurality of pockets, one of said pockets having a substantially longitudinally extending opening and the other of said pockets being disposed between said first mentioned pocket and the material forming said 25 garment and having an opening extending in angular relation with said first mentioned opening, a closure, and means to hold the same in position to close one of said openings and in operatively movable relation 30
- with one of the sides of the other of said 35 openings.
5. In a garment, the combination of a pair of pockets, one of said pockets having a vertically extending opening, and the other of said pockets having an opening in angular relation therewith, a flap secured adjacent the edge of said vertical opening and adjacent the waist band of said garment, and means adjacent said waist band for securing said flap in closed position, said flap 40 when in such closed position being adapted to lie adjacent to and move with a side of said vertically extending opening when said side is displaced to give access to said first mentioned pocket. 45
6. In a garment, the combination of a pair of pockets, one of said pockets having a substantially longitudinally extending opening and the other of said pockets being disposed between said first mentioned pocket 50 and the material of which the garment is made and having an opening angularly disposed with respect to said first mentioned opening, a closure for said angularly disposed opening and means operative to retain 55 said closure in position to close said opening and in unitarily movable relation with the material forming a side of said first mentioned pocket. 60

In witness whereof I have hereunto set 65 my hand this 23rd day of May, A. D. 1919.

GABRIEL BLUM.
